REMOVAL OF SULFUR COMPOUNDS FROM HYDROCARBON FRACTIONS

John E. Connor and Clifford E. Gustafson, Elizabeth, N. J., assignors to Standard Oil Development Company, a corporation of Delaware

Application April 23, 1949, Serial No. 89,312

7 Claims. (Cl. 196—32)

1

The present invention is concerned with the removal of sulfur compounds particularly mercaptan constituents from hydrocarbon fractions. The invention is more particularly concerned with the removal of these sulfur compounds from hydrocarbon fractions which boil in the motor fuel boiling range. In accordance with the present invention these undesirable sulfur constituents are removed from hydrocarbon fractions by treating the same with an alkali hydroxide solution which contains dissolved therein a quantity of elementary sulfur. In accordance with the preferred adaptation of the present invention the sulfur is dissolved in the alkali hydroxide solution at an elevated temperature. This is preferably accomplished by adding sulfur to a relatively concentrated alkali hydroxide solution followed by diluting the same to a preferred treating concentration.

It is well known in the art to treat petroleum oils by various procedures in order to remove objectionable compounds, as for example sulfur compounds therefrom. For example, it is known to treat petroleum fractions boiling in the motor fuel boiling range and in the general range below about 700° F. with various chemical reagents such as, sodium or potassium hydroxide solutions. Also, it has long been known that weakly acidic materials, such as mercaptans, are reactive to various degrees with basic materials. One method for the removal of mercaptan compounds from hydrocarbon streams containing the same has been to treat these streams with a reagent which is insoluble in the hydrocarbon stream but which contains alkali type of material which reacts with the mercaptan constituents. Such treating agents have normally been aqueous solutions of an alkali material. The reaction product between the treating solution and the mercaptan is a basic salt of the mercaptan. Normally, such salts exhibit some solubility in the aqueous phase. However, this solubility decreases as the molecular weight or branchiness of the hydrocarbon structure of the mercaptan increases. Therefore, caustic solutions when they are only spent to a small extent in mercaptide salts will not give any further reduction in mercaptan content despite the fact that these treating solutions have a large residual free caustic content. The

art has also recognized that the efficiency of the spent caustic can be partially or fully restored by regeneration of these solutions. The regeneration normally consists of removal of a part or all of the mercaptide salts by means of hydrolysis and vaporization or by oxidation.

One method is to employ steam regeneration for the revivification of caustic solution spent in mercaptan removal from hydrocarbon streams. 10 The steam regeneration is normally carried out in a packed tower or a tower provided with bubble plates or pierced type tray plate design. The steam hydrolyzes the mercaptide salts to the corresponding mercaptans which are stripped out 15 by the steam vapors and taken overhead. The regenerator also serves as a means of adjusting the gravity of the caustic solution, which has been shown to be critical. The regenerated caustic is withdrawn from the bottom of the regeneration tower and reused in the extraction stage of 20 the system wherein the caustic contacts the hydrocarbon stream through suitable mixing devices for further extraction of mercaptans by the same caustic.

25 Thus, it is apparent that sodium hydroxide per se is not entirely satisfactory for the removal of objectionable mercaptan constituents from hydrocarbon fractions containing the same. It has now been discovered however that providing the alkali hydroxide solution is pretreated in a manner to dissolve sulfur therein, unexpected and desirable results are secured with respect to the removal of mercaptan constituents. The present invention may be readily understood by reference to the drawings illustrating embodiments 30 of the same. Figure 1 illustrates an adaptation of the invention wherein sulfur is added to the alkali hydroxide solution and the same then heated to a temperature within a critical range. Figure 2 illustrates an adaptation of the invention 35 wherein the heating is secured by dilution of a relatively concentrated alkali hydroxide solution.

40 Referring specifically to Figure 1, a feed stream which for the purpose of illustration is assumed to be a hydrocarbon fraction boiling in the range below about 420° F. is introduced into a depropanizing zone 1 by means of line 2. Temperature and pressure conditions are adjusted in zone 1 to remove overhead by means of line 3 a stream

comprising propane and lower boiling constituents. Hydrocarbon fractions boiling above the boiling range of propane is removed from the bottom of zone 1 by means of line 4 and introduced into a debutanization zone 5. A stream comprising butane is removed overhead from zone 5 by means of line 6 while a stream substantially free of constituents boiling below the boiling range of butane is removed from the bottom of zone 5 by means of line 7.

This stream is introduced into zone 8 wherein it is contacted with an alkali hydroxide solution which is introduced into zone 8 by means of line 9 and withdrawn by means of line 10. The treated oil is withdrawn from zone 8 by means of line 11 and introduced into zone 12 wherein the same is contacted with a doctor solution¹ which is introduced by means of line 13 and withdrawn by means of line 14. The doctor treated oil is withdrawn from zone 12 by means of line 15 and introduced into water washing zone 16 wherein it is contacted with water which is introduced by means of line 17 and withdrawn by means of line 18. The finished oil product is withdrawn from zone 16 by means of line 19 and further handled as desired. It is to be understood that zones 1, 5, 8, 12 and 16 may comprise any suitable number and arrangement of stages.

In accordance with the present invention the alkali hydroxide solution employed in zone 8, which for the purpose of illustration is assumed to be a sodium hydroxide solution, is prepared by introducing the sodium hydroxide solution into zone 20 by means of line 21. Sulfur is introduced into zone 20 by means of line 22. Suitable mixing devices may be employed. The stream is withdrawn from zone 20 by means of line 23 and introduced into heating zone 24 wherein the same is heated to a temperature in the range from about 150° F. to 190° F. The sodium hydroxide solution containing the dissolved sulfur is then used as described to treat the naphtha in zone 8.

Referring specifically to Figure 2 it is assumed for the purpose of illustration that the operation is conducted as described with respect to Figure 1, except with respect to the preparation of the sulfurized sodium hydroxide. Referring specifically to Figure 2, a relatively concentrated solution of sodium hydroxide is introduced into zone 30 by means of line 31. Sulfur is added to zone 30 by means of line 32. The concentrated solution of sodium hydroxide containing sulfur dispersed throughout its volume is withdrawn from zone 30 by means of line 33 and mixed with water which is introduced by means of line 34. In accordance with the preferred adaptation, the mixture is secured by passing the same through a mixing device 36. Due to the dilution effect, the temperature of the sodium hydroxide solution is raised to a temperature within the range from about 150° F. to 190° F., thus, securing the dissolving of the sulfur in the sodium hydroxide. If necessary the temperature may be adjusted to within this range by means of heating-cooling zone 35. This sodium hydroxide solution containing the dissolved sulfur is introduced into

zone 8 by means of line 9 in an operation such as described in Figure 1. It is to be understood that the sulfurized sodium hydroxide solution need not be hot when used to treat the oil stream in zone 8.

The present invention is broadly concerned with the use of a sulfurized alkali hydroxide solution for the removal of mercaptan constituents from hydrocarbon fractions containing the same. 10 The invention is particularly adapted for the treatment of hydrocarbon fractions boiling below about 700° F. especially those fractions boiling in the motor fuel boiling range (80° F.-420° F.). Especially desirable feed stocks for which the 15 present invention is adapted are those fractions which boil in the range from about 250° F. to 420° F. It is within this range that conventional alkali hydroxide solutions as for example sodium hydroxide solutions are not particularly effective in removing mercaptan constituents.

The alkali hydroxide solution may be any suitable solution, as for example, sodium or potassium hydroxide. In general, the alkali and the alkaline earth metal hydroxide solutions are satisfactory. These metals among others comprise sodium, potassium, lithium, rubidium and cesium.

The amount of sulfur used in conjunction with the alkali may vary appreciably. However, it is preferred that the amount be from 5 to 10 parts 30 of dry alkali by weight per 1 part of sulfur. If too little sulfur is used, satisfactory removal of the mercaptans is not secured, whereas, on the other hand if too much sulfur be employed based upon the dry metal hydroxide, the mercury 35 number¹ of the treated oil will increase prohibitively. The concentration of the soda employed in the treatment of the feed oils should preferably be above 10° Bé. It is desirable that the concentration of the fresh soda should be in 40 the range from 14° to 16° Bé.

As pointed out heretofore, it is necessary that the alkali metal hydroxide solution containing the sulfur be heated to a temperature in the range from about 150° F. to 190° F. While this may be done by adding sulfur to a 14° to 16° Bé. soda solution and heating the same to a temperature within this range, a particularly desirable method in accordance with the present invention is to add sulfur to an alkali metal hydroxide solution having a concentration in the range from about 30° to 35° Bé., and to dilute this solution to a concentration in the range from about 14° to 16° Bé. Under these conditions the temperature of the diluted solution will increase to within the desired 55 temperature range.

The present invention may be more readily understood by the following examples illustrating the same.

EXAMPLE 1

A 15° Bé. sodium hydroxide solution was mixed with sulfur in the amount of one part of sulfur by weight based upon 10 parts of dry soda by weight. This sulfurized sodium hydroxide solution was used to treat a hydrocarbon fraction boiling in the range from about 80° F. to 420° F. The results secured were compared with the treatment of the same fraction utilizing a 15° Bé. sodium hydroxide solution containing no sulfur. The results of 60 these operations are as follows:

¹ "Doctor sweetening process."—In this process the mercaptans are first converted to oil soluble lead mercaptides. This is effected by contacting the oil with "doctor solution," i. e., lead oxide dissolved in an aqueous caustic soda solution. The naphtha containing the lead mercaptan has injected into it a sulfur solution; the result being the conversion of the mercaptides to a disulfide, and the formation of insoluble lead sulfide.

² Test to determine reactive sulfur present in sweetened stock. (Mercury number is equivalent to the mg. of reactive sulfur per 100 cc.)

Comparison of sour naphthas after caustic treatment

ITEM TREATED	Cu#	GM Gum ¹	Corro-sion ²	Hg#	Break-down ³ (mins.)	Octane Numbers	
						Clear	4+cc TEL
Untreated Feed	34	4.8	Pass	0+	10	69.9	78.3
Same Stock-soda washed	17	4.6	do	0+	50	70.2	78.4
Same Stock-washed with sulfurized soda	5	2.4	do	1-	50	70.5	78.3

¹ Describe GM gum test or give A. S. T. M. number where it is described.

² Corrosion test.—This consists in immersing bright copper strip for 3 hours in the oil maintained at 212° F. to determine the presence of "corrosive" sulfur in the oil as indicated by discoloration and pitting of the copper.

³ Breakdown introduction for a 2# drop. 25 cc. of oil are placed in a bomb at a temperature of 212° F. under oxygen pressure of 100# per sq. in. The time in minutes is measured during which the pressure drops 2# and taken as the breakdown.

From the above it is readily apparent that the use of sulfurized sodium hydroxide produces a treated stock of considerably higher quality than that secured when treating with an unsulfurized sodium hydroxide solution.

EXAMPLE 2

A prime cut naphtha having a copper number of 37 was treated with a sodium hydroxide solution (15° Bé.) to which was added one gram of sulfur per 10 grams of dry sodium hydroxide. Another portion of the prime cut naphtha (80° to 420° F.) was treated with a soda solution (15° Bé.) which did not contain any sulfur. The results were as follows:

Feed	Copper No.
Naphtha	37.0
After 15° Bé. soda wash	16.0
After soda+sulfur	8.5

EXAMPLE 3

A debutanized feed naphtha having a copper number of 33½ was treated with a 15° Bé. soda solution prepared in accordance with the present invention and with a soda solution which did not contain any added sulfur. After treatment with the soda the naphtha was doctor sweetened. The results of these operations are as follows:

	Copper No.	Mercury No.
Debutanizer Bottoms	33½	13½
After 15° Bé. soda+sulfur	8	1
After 15° Bé. soda	16	1

EXAMPLE 4

A debutanized naphtha was treated with a 15° Bé. caustic solution. Other portions were treated with a 15° Bé. caustic solution containing sulfur in accordance with the present invention. The respective caustic solutions were withdrawn from the treated naphtha and reused on fresh naphtha. The copper number of the respective treated naphthas were determined with the following results.

Debutanizer Bottoms— Soda used	Copper No. 34— Soda+sulfur used
One treat	16
Two treats	23
Three treats	26
Four treats	31
	8
	9
	10
	17
	27

ITEM TREATED	Cu#	GM Gum ¹	Corro-sion ²	Hg#	Break-down ³ (mins.)	Octane Numbers
Untreated Feed	34	4.8	Pass	0+	10	69.9
Same Stock-soda washed	17	4.6	do	0+	50	70.2
Same Stock-washed with sulfurized soda	5	2.4	do	1-	50	70.5

¹ Describe GM gum test or give A. S. T. M. number where it is described.

² Corrosion test.—This consists in immersing bright copper strip for 3 hours in the oil as indicated by discoloration and pitting of the copper.

³ Breakdown introduction for a 2# drop. 25 cc. of oil are placed in a bomb at a temperature of 212° F. under oxygen pressure of 100# per sq. in. The time in minutes is measured during which the pressure drops 2# and taken as the breakdown.

It is apparent that not only is a marked improvement secured in the removal of the mercaptans when using the sulfurized caustic solution, but also that the solution can be reused with marked effect over an unsulfurized caustic solution. The above data shows for example that when the sulfurized caustic solution is used the third time, the treated naphtha had a copper number of 10, whereas, when the unsulfurized caustic solution was used a third time the naphtha had a copper number of 26.

These naphthas were subsequently doctor sweetened to a copper number less than one-half. The amount of doctor solution required with respect to the above series of treatments is as follows:

35	Soda used	When using Sulfurized Soda
One treat		50% of amount used when using non-sulfurized soda.
Two treats		30% of amount used when using non-sulfurized soda.
30 Three treats		38% of amount used when using non-sulfurized soda.
Four treats		55% of amount used when using non-sulfurized soda.

As pointed out heretofore, the concentration of the caustic used is preferably in the range from about 14° to 16° Bé. The quantity employed may vary appreciably, but in general it is preferred to use from about 10% to 30% by volume of caustic solution based upon the volume of oil being treated. With respect to the examples given, approximately 20% by volume of caustic was employed based upon the volume of oil treated.

Having described the invention it is claimed:

1. Improved process for the removal of mercaptan compounds from a hydrocarbon fraction containing the same which comprises adding sulfur to an aqueous alkali metal hydroxide solution, heating the same and thereafter contacting the hydrocarbon fraction with said aqueous alkali metal hydroxide solution, whereby said mercaptan compounds are removed from said hydrocarbon fraction.

2. The process as defined by claim 1 wherein said hydrocarbon fractions boils in the range from about 250° F. to 420° F. and wherein said alkali metal hydroxide solution comprises sodium hydroxide.

3. Process for the removal of mercaptan compounds from petroleum fractions boiling in the range from about 80° F. to 420° F. which comprises adding sulfur to an aqueous metal hydroxide solution, heating the mixture to a temperature in the range from about 150° to 190° F. and thereafter contacting said petroleum fractions with said aqueous metal hydroxide solution

whereby said mercaptan compounds are removed from said fractions.

4. Process as defined by claim 3 wherein said alkali metal hydroxide solution comprises a sodium hydroxide solution having a gravity in the range from about 14° Bé. to 16° Bé. and wherein the amount of sulfur added is in the range from about one part of sulfur by weight per 5 to 10 parts of dry caustic.

5. Process for the removal of mercaptan compounds from petroleum fraction boiling in the range from about 80° F. to 420° F. which comprises adding sulfur to an aqueous alkali metal hydroxide solution having a gravity in the range from about 30° Bé. to 35° Bé., diluting said alkali metal hydroxide solution with water, whereby an elevated temperature is secured, allowing the diluted mixture to cool and then contacting said petroleum fraction with said diluted cooled alkali metal hydroxide solution whereby said mercaptan compounds are removed from said petroleum fraction.

6. Process as defined by claim 5 wherein the

amount of sulfur added is one part of sulfur by weight per 5 to 10 parts of dry caustic by weight.

7. Process as defined by claim 6 wherein said alkali metal hydroxide solution comprises a sodium hydroxide solution.
